UNITED STATES PATENT OFFICE.

HENRY F. G. FUCHS, OF JERSEY CITY, NEW JERSEY.

DESIGN FOR A BADGE.

SPECIFICATION forming part of Design No. 21,898, dated October 18, 1892.

Application filed March 31, 1892. Serial No. 427,283. Term of patent 7 years.

To all whom it may concern:

Be it known that I, HENRY F. G. FUCHS, a citizen of the United States, residing at Jersey City, in the county of Hudson and State of New Jersey, have invented and produced a new and original Design for a Badge or Boudonnière, of which the following is a specification, reference being had to the accompanying drawing, forming part thereof.

10 The drawing shows a front elevation of my design for a badge or boudonnière.

The leading feature of my design consists of three or more leaves substantially circular in outline, grouped about a stem, and having

a winged figure placed substantially in the center of the leaves so grouped together.

In the drawing, A is the stem, B B the leaves with edges b b, and E a figure with wings B'.

C C are stamens, and D a back leaf.

What I claim, and desire to protect by Letters Patent, is—

The design for the badge, substantially as herein shown and described.

HENRY F. G. FUCHS.
